UNITED STATES PATENT OFFICE.

MAX KRAVITZ, OF PHILADELPHIA, PENNSYLVANIA.

GAS-BURNER.

1,212,510.

Specification of Letters Patent. Patented Jan. 16, 1917.

Application filed May 2, 1916. Serial No. 94,964.

To all whom it may concern:

Be it known that I, MAX KRAVITZ, a subject of the Czar of Russia, residing at Philadelphia, in the county of Philadelphia and 5 State of Pennsylvania, have invented new and useful Improvements in Gas-Burners, of which the following is a specification.

This invention relates to gas burners, and particularly to a gas burner for stoves, 10 ranges, etc., embodying means for producing a gas flame of full strength or of reduced strength, so that when desired the full heat of the burner may be obtained for cooking and analogous purposes requiring compara- 15 tively high heat, or a flame of low character or strength produced for "simmering" or other analogous purposes.

The primary object of the invention is to provide a burner equipped with independent 20 burner sections, one of which is used when a full flame is desired and the other when a small or simmering flame is desired, together with a valve mechanism for controlling the flow of gas to both of said burner sections 25 through the instrumentality of a single valve, whereby the supply of gas to both burners may be simultaneously cut off or the gas allowed to flow to one or the other of the burners, but not to both simultaneously.

30 A further object of the invention is to provide burners having independent supply conduits in combination with a single valve for positively supplying the gas thereto and which will supply the gas to either burner 35 with a proper and regulated proportion of air to support combustion.

With these and other objects in view, the invention consists of the features of construction, combination and arrangement of 40 parts hereinafter fully described and claimed, reference being had to the accompanying drawing in which:

Figure 1 is a vertical transverse section through a gas stove and burner equipped 45 with the present invention. Fig. 2 is a horizontal section through the same on the line 2—2 of Fig. 1. Fig. 3 is an enlarged detail sectional view on the line 3—3 of Fig. 1. Fig. 4 is a perspective view of the valve 50 plug. Fig. 5 is a longitudinal section thereof.

Referring to the drawing, the numeral 1 designates an ordinary form of gas stove, provided with the usual burner 2, connected with a fuel supply conduit 3 communicating 55 with air supply inlets 4. The gas main or supply pipe 5 is arranged in a suitable po-

sition and is in communication with the conduit 3 through a controlling valve 6.

The above described construction may be that common to gas stoves of ordinary type. 60

The burner 2 is provided and employed as a main burner for securing a full heating flame. For the purpose of securing a smaller flame or flame of relatively lower strength, I provide an auxiliary burner 7 which is centrally positioned within the main burner 2. 65 This auxiliary burner includes a semi-hemispherical body 8 having a series of jet nozzles or perforations 9 formed therein, which burner communicates with a fuel supplying pipe or duct 10 having one or more air inlets 11, said pipe or duct 10 being entirely independent of the pipe or duct 3. The burner 7 is designed to be employed for producing a low degree of heat for the purpose of keeping 70 the contents of a kitchen utensil or other receptacle in a heated condition, or in a simmering state, but not so hot as to actively affect the contents of the utensil. Thus by the use of the main burner 2 a full strength 75 flame may be secured for ordinary cooking or heating purposes, while by the use of the burner 7 a low degree of heat may be obtained for merely maintaining the contents of a receptacle at a determined compara- 80 85 tively low temperature.

The valve 6 may take the place of an ordinary controlling valve, but in the present instance is of novel construction and is designed to control the supply of gas to both 90 burners through the respective conduits 3 and 10. This valve comprises a casing 12 having aligned admission and discharge ports 13 and 14 which are in respective communication with the gas supply pipe 5 and with 95 the conduit 3, and a valve proper 15 which is mounted within said casing for controlling said ports and also establishing communication between the port 13 and a port or passage 16 connecting the valve casing with the 100 pipe 10. The said port or passage 16 is formed in a union or nipple 17 connecting the lower end of the valve with the approximate end of the pipe 10, and, as shown, the valve 15, which is preferably of the 105 tapered plug type, is provided with a diametrical passage 18 for connecting the ports 13 and 14 and is provided also with a vertical groove or recess 19 in its side communicating with a vertical port or passage 20 110 terminating in a threaded socket receiving the upper end of the union or nipple 17.

These ports are so arranged in connection with each other and with the passages that when the handle 21 of the plug valve is turned to the intermediate position A in Fig. 5 3 the passage 18 will connect the ports 13 and 14 for the flow of gas from the main 5 to the main burner 2 commingled with air entrained through the inlets 4; while when the valve handle is turned to one of the right 10 angular positions B the passage 18 will be moved out of alignment with the ports 13 and 14 to cut off the supply of gas to the main burner, but at the same time connecting the admission port 13 with the groove 15 19 and port 20 for the supply of gas to the auxiliary burner 7. In the third or other right angular position C all of the ports and passages will be in a blank position or out of communication with each other, thus 20 cutting off the supply of gas to both burners. It will thus be understood that in position C, which is the normal position of the valve, both burners will be cut off from connection with the fuel supply main, but that 25 when it is desired to use the main burner 3 the valve is turned to the first-named position A so that a full supply of gas mixed with air will pass such burner for ordinary cooking or heating purposes where the use 30 of a full hot or intense flame is desired. When it is desired however to secure merely a low flame for simmering or other purposes, as above set forth, the supply of gas to the small burner may be secured by moving the 35 valve to position B, in which operation the flow of gas to the main burner will be cut off. Hence it will be seen that but a single valve is required in the use of this invention to control the flow of gas to both burners for independently supplying each burner 40 and at the same time cutting off the flow of

gas to the other burner, and that by means of the same valve the flow of gas to both burners may be cut off, thus simplifying the construction of the burner mechanism and 45 reducing the cost of manufacture while at the same time rendering the operation simpler, more convenient and safer than by the use of a plurality of valves, since in the adjustment of the single valve the supply of 50 gas may be positively controlled and the danger of leaving one or the other of the fuel supply conduits open for communication with the main conduit avoided.

55

I claim:—

In a gas stove or range, the combination, with a main burner, an auxiliary burner inclosed thereby, a main supply pipe, feed conduits leading to the respective burners, a valve casing provided with an inlet port 60 communicating with the main gas supply pipe and with discharge ports communicating respectively with said feed conduits, and a plug valve mounted in said casing and provided with a diametrically extending 65 port for connecting said inlet port with the discharge port leading to the main burner conduit, said plug having also a vertical feed port opening through one of its sides and its bottom, said port being adapted for 70 connecting the inlet passage of the valve casing with the auxiliary burner feed conduit, said valve passages being so disposed as to adapt the valve to be moved to different feed positions to connect one or the 75 other of said burners with the main supply pipe and to a third position to cut off communication between both burners and the main supply pipe.

In testimony whereof I affix my signature.

MAX KRAVITZ.
